ELECTRIC CURRENT DISTRIBUTOR

Edward B. Nowosielski, Bloomfield, N. J., assignor to Edison-Splitdorf Corporation, West Orange, N. J., a corporation of New Jersey

Application October 15, 1941, Serial No. 415,087

8 Claims. (Cl. 200—24)

This invention relates to electric current distributors and more particularly to distributors for the ignition current of internal combustion engines. The invention has a special application in ignition systems for aircraft which have large numbers of cylinders and which are to fly at high altitudes in the rarified atmosphere.

Ignition current distribution is accomplished by moving a distributing means or rotor past successive leading-out electrodes connected to the engine spark plugs. The distributing rotor is supplied with high-voltage current impulses, as from an ignition generator or magneto, which are timed with the rotor movement to occur at the instants the rotor moves past, or registers with, successive ones of the leading-out electrodes. Thus, the voltage impulses encounter relatively short air-gaps to the successive leading-out electrodes, which gaps they are enabled to jump and be conducted to the respective engine spark plugs.

At each spark jump, or breakdown of an air-gap, the immediate region of the air is placed in a highly ionized state and becomes a good conductor of electricity. This ionized state has a definite duration and, because of the separating movement between the rotor and the leading-out electrodes, causes an arc to trail after each electrode. Typically, each voltage impulse may not die out completely before the occurrence of the next succeeding one with the result that a substantial residual voltage is applied to the rotor between impulses. This residual voltage prolongs the duration of each spark and lengthens the trailing arcs. Increased engine speed also tends to lengthen these arcs. Accordingly, it is necessary to provide ample dielectric spacing between succeeding leading-out electrodes in order that successive firing or distributing positions may not be bridged by the trailing arcs and cause the current to be deviated to the wrong engine spark plugs to cause misfiring.

In the usual distributor all the leading-out electrodes are arranged at equal intervals in one circle around the distributor block and are fed successively by a central distributor arm. When such a distributor is to have a large number of leading-out electrodes to serve an engine having a large number of cylinders, as of twelve or more, the distributor block must have an unduly large diameter in order to provide ample dielectric spacing between adjacent electrodes to prevent bridging of successive distributing positions. The use of such a large block introduces difficult problems in manufacturing and in meeting size

and cost requirements. These problems in distributors are particularly acute in connection with aircraft engines, particularly those which are to fly at high altitudes since the effective dielectric spacing between successive distributing positions in the distributor must for this application be evermore increased because of the decreased dielectric strength of the atmosphere.

It is an object of my invention to provide a new and improved distributor arrangement wherein such possible misoperation as is above noted is effectively prevented, and particularly it is an object to provide a distributor adapted to serve engines efficiently and dependably which have large numbers of cylinders and which are to operate under conditions where the dielectric strength of the atmosphere is reduced.

It is another object to provide an improved distributor arrangement wherein a large dielectric spacing and insulation is obtained between successive distributing positions.

It is another object to provide an improved current distributor, having an aggroupment of leading-out electrodes, wherein the electrodes are selected successively at space intervals greater than the distances between adjacent electrodes.

It is another object to provide a distributor having a plurality of distributing parts coacting in a novel relationship.

It is a further object to provide an improved distributor assembly having a large number of leading-out electrodes for serving engines having many cylinders while yet having such improvements in construction as are conducive to reliability and durability in operation and economy in manufacture.

It is another object to provide a simplified distributor and current-generator arrangement for the purposes above stated, and more particularly to provide a compact magneto and distributor arrangement of novel design adapted to serve efficiently and reliably multi-cylindered engines which are to operate in the rarified atmosphere.

Other objects of my invention will more fully appear from the following description and the appended claims.

In the description of my invention reference is had to the accompanying drawings, of which:

Figure 1 is a cross-sectional view of a distributor constructed in accordance with one embodiment of my invention and taken substantially along the line 1—1 of Figure 2;

Figure 2 is a top fractional view of the struc-

ture of Figure 1 as seen with the top housing section removed and with a part broken away;

Figure 3 is a sectional view taken substantially along the line 3—3 of Figure 1;

Figure 4 is a top view of one of the distributor units employed in this embodiment of my invention;

Figure 5 is a side view of the unit shown in Figure 4;

Figure 6 is a partially diagrammatic view of circuits and structure illustrating a second embodiment of my invention and as adapted to a current generator one part thereof appearing in section on the line 6—6 of Figure 7; and

Figure 7 is a view partially diagrammatic of the distributor arrangement shown in Figure 6.

The illustrative embodiment of my invention herein shown in Figures 1—5 comprises a plurality of separate auxiliary distributor units of which in the present instance there are three designated respectively as 1a, 1b and 1c. These units each comprise a series of leading-out electrodes 2, a distributor rotor 3 and an input terminal 4 which constitutes an intermediate leading-out electrode of the system. The units are disposed in circular arrangement about a predetermined axis 5. Journalled at this axis is a main distributor rotor 6 which is adapted to register successively with the input terminals 4 to feed current to the respective distributor units. These parts are housed in a casing including a central section 10 having an outlet neck 10' for leading-out conductors, an upper end section 11 bolted to the central section at 12 and a lower end section 13 bolted to the central section at 14. In the present instance the distributor units are spaced about the axis 5 at equal angular intervals of 120°. Such even disposition of the units about the axis 5 permits a compact arrangement of the distributor parts, but it will be understood that my invention is not necessarily limited to an equal spacing of the units. Rather, in its broader aspects, as will hereinafter more fully appear, my invention contemplates any desired physical arrangement of the auxiliary distributors with the limitation that their respective input terminals constitute the electrodes of a main distributor driven in a predetermined timing relationship to the auxiliary distributors.

The lower casing section 13 has a central cylindrical portion 13' open to the bottom and terminating at the top into a bearing housing 16 which extends up into the central casing section 10. The housing is lined by a bushing 17 in which there is journalled a sleeve 18. This sleeve has an enlarged diameter portion 18' at the top terminating into an outwardly extending flange 19; this flange forms a support for the main rotor 6 as is hereinafter explained. The sleeve 18 is received by a shaft 21 which constitutes the drive shaft for the magneto. This shaft is keyed at 22 to a drive gear 23 disposed within the cylindrical casing portion 13' between the lower end of the sleeve 18 and an integral collar 24 on the shaft. A nut 26 threaded on the upper end of the shaft 21 within the enlarged-diameter sleeve portion 18' serves to hold the sleeve 18 and gear 23 tightly in place on the shaft.

Integral with the lower casing section 13 are partitioning walls 15 (see Figure 3) which extend out from the cylindrical casing portion 13' and form three separate wells 28 equidistantly spaced about this cylindrical casing portion. These wells communicate through windows 29 with the interior of the cylindrical casing portion, and have

shouldered recesses 30 at the bottom which form seats for bearings 31, as are shown in Figure 1. The wells have circular openings 32 at the top. Into these openings are fitted annular caps 33 which carry bearings 34 vertically in line with the bearings 31 just mentioned. The caps have lugs 35 at the sides which are secured to the partitioning walls 15 by screws 36. Shafts 37 are journalled in the bearings 31 and 34 and have gears 38 secured thereto within the wells 28. These gears project through the respective windows 29 to mesh with the drive gears 23. The shafts 37 project up into the central casing section 10 and form spindles for the rotors 3 of the respective distributor units as will hereinafter more fully appear.

Each of the distributor units comprises a hollow cylindrical body 39 of insulating material having the respective annular cap 33 as a base, the body being secured to the cap in any suitable manner. Each body 39 has a counterbore 40 at the top and has a series of L-shaped conductor elements 41 embedded therein and projecting up into the counterbore 40 to form the leading-out electrodes 2 above-mentioned. In the present instance there are in each unit six of these electrodes equidistantly spaced.

For each conductor element 41 there is provided a lateral opening 42 in the body 39 which runs from a point directly beneath the conductor element through a side face 43 of the body. These openings form channels for leading-out conductor wires 44 which connect to the respective conductors elements through piercing screws 45, as is shown in Figure 1. The openings 42 are grouped into two sets of three each, which sets are disposed at opposite sides of the body 39. The openings for the two conductor elements adjacent the face 43 are located at an upper level; those for the two conductor elements opposite the face 43 are located at a lower level; while those for the two intermediate conductor elements are located at an intermediate level (see Figures 4 and 5). In order to permit an advantageous aggroupment of the leading-out conductor wires 44, the openings of the respective sets are led out through the face 42 at points vertically in line, and the distributor units are oriented so that their faces are directed toward the outlet neck 10' as a focal point. For instance, the faces of the distributor units 1b and 1c will be thus directly adjacent the outlet neck 10' and the face of the remaining distributor unit 1a will be directed between the other units towards this outlet neck. By having the conductor wires 44 lead out vertically in line from opposite sides of the face 43 of this unit 1a, the conductor wires may be led conveniently to the outlet neck 10' in groups of three at opposite sides of the bearing housing 16, between this housing and the respective distributor units 1b and 1c, as is shown in Figures 1 and 2.

The auxiliary distributor rotors 3 of the respective distributor units each comprise a nob-like body 50 of insulating material into which there is embedded a depending sleeve 51 adapted to fit onto the respective shaft 37 and be locked or keyed thereto in any suitable manner. Also embedded into the body 50 is the input terminal 4, which is at a point axially above the sleeve 51, and a distributor conductor element 52 riveted to the terminal 4 and extending down therefrom and then radially outwardly from the body 50 into the counterbore 40 of the body 39. Upon rotation of the rotor 3 this conductor element 52

registers in recurring succession with the group of six leading-out electrodes 2 of the unit.

The main distributor rotor 6 comprises a saucer-shaped body of insulating material 53 having a lower flat face fitting the upper flanged end 19 of the sleeve 18 and secured thereto by screws 20. Embedded into this body 53 is a spider-shaped conductor element 54 having a plurality of feeding-out electrodes 55—there being four in the present instance particularly designated as 55a, 55b, 55c and 55d respectively—which are spaced equidistantly about the spider and which project out through the body 53. As is herein-after explained, these electrodes 55 are adapted to register successively with the input terminals 4 of the distributor units as the rotor 6 is turned. Also embedded in the body 53 within a central dome portion 53' thereof, is a tubular conductor element 56 which is suitably united to the spider conductor element 54 and extended up to the top of the dome portion. In this tubular element 56 there is a terminal button 57 pressed upwardly by a compression spring 58. This button bears against the head of a pointed screw 59 which is threaded into a metallic plate 60 that is embedded in an insulating block 61 carried by the top casing section 11. The block 61 has a laterally extending opening 62 leading out through the side thereof from directly above the plate 60. In this opening there is a supply conductor 63 which is pierced by the pointed end of the piercing screw 59 and thus locked in place and connected to the terminal button 57 through the screw 59. This supply conductor leads out of the distributor casting as through an opening 64 and makes connection with a source of ignition current such as an ignition generator or magneto (not shown).

A booster circuit for supplying ignition current to the rotor 6 during engine starting may comprise a metallic ring 65 embedded in the rotor body 53 and provided with feeding-out electrodes 70 interposed between the electrodes 55 of the spider conductor element 54, which electrodes 70 have lugs 70' connected as by welding to the ring 65. This ring projects up above the level of the body 53 as is shown in Figure 1. Directly above the end of the ring but spaced therefrom is the head of a pointed screw 66 which threads into a metallic plate 67 that is embedded in the insulating block 61. A lateral opening 68 in the block 61 above the plate 67 includes a supply conductor 69. This conductor is pierced and locked in place by the pointed end of the screw 66, and leads from the casing to a booster source of ignition current as through the opening 64.

In accordance with the present invention the feeding-out electrodes 55 of the main rotor 6 are to register in recurring succession with the input terminals 4 of the distributor units as the rotor is turned. In the present instance there are four feeding-out electrodes 55 and three input terminals 4, the electrodes and terminals being each equidistantly spaced about the axis 5. As appears in Figure 2, when the feeding-out electrode 55a is in registration with the input terminal 4 of the distributor unit 1a the next succeeding feeding-out electrode 55b is at a distance of one-third the interval between succeeding electrodes from the input terminal 4 of unit 1b; the next further feeding-out electrode 55c is at a distance of two-thirds this interval from the input terminal 4 of the unit 1c; and the remaining feeding-out electrode 55d is at a distance of a full interval from the input terminal 4 of unit 1a. Thus a

rotation of the rotor 6 through one-third of the interval just mentioned—which is through one-twelfth revolution thereof—will cause it to register with the distributor unit 1b; a further rotation through another one-twelfth revolution of the rotor will cause it to register with the distributor unit 1c and a still further rotation of a further one-twelfth revolution of the rotor will cause it to register with the distributor unit 1a. As the rotor 6 is continued to be rotated this process is repeated to cause the rotor to come into registration with the distributor units in recurring succession, the several distributor units being brought successively into registration with the rotor for each one-fourth revolution of the latter. Thus, the provision of a plurality of feeding-out electrodes on the rotor permits the rotor speed to be very much reduced. Yet at no time will the rotor register simultaneously with more than one of these distributor units, but will register with the units in regular recurring sequence. A fundamental requirement for fulfilling the condition that the rotor 6 be able to register with the distributor units in regular recurring sequence is that successive input terminals 4 be progressively spaced in the direction of advance of the rotor 6 at equal intervals from the respective preceding feeding-out electrodes 55 of the rotor. So long as the input terminals 4 and electrodes 55 are each equidistantly spaced about the axis 5, as is here the case, it will be seen that there will be realized the condition just mentioned provided the number of the electrodes 55 and of the associated input terminals 4 shall not have a common factor. However, it will be understood that the rotor may be made to register with the distributor units in regular recurring succession without both the input terminals 4 and feeding-out electrodes 55 being respectively equidistantly spaced, and that the rule that they shall have no common factor does not then apply.

Further, in accordance with the present invention, each auxiliary rotor 3 is to register in recurring succession with its respective group of leading-out electrodes 2 at the instants the input terminal 4 of the unit is brought into registration with the electrodes 55 of the main rotor 6. In other words, the main rotor 6 is to feed the supply current to the auxiliary distributor units in recurring succession, and, in turn, the auxiliary rotors 3 of these units are to distribute this supply current to its associated leading-out electrodes in succession. Since in the present example the main rotor has four feeding-out electrodes 55 and there are three distributor units each having six leading-out electrodes 2, the auxiliary rotors 3 are each to turn through one-sixth revolution for each one-fourth revolution of the main rotor—the amount of turning of the main rotor required to cause it to register once with each of the units as has been above explained. The drive ratio of the main and auxiliary rotors is thus 3:2, which is the ratio of the gears 38 and 23 above described. While each auxiliary rotor 3 is driven at the speed of the others they are, relatively to another, offset angularly about their respective shafts with respect to their leading-out electrodes. For instance, as is shown in Figure 2, when the distributing element 52 of unit 1a is in registration with an electrode 2, the distributing element 52 of unit 1b is set back one-third of the interval between adjacent electrodes 2 and the distributing element 52 of unit 1c is set back two-thirds the distance of such interval. Thus, for the rel-

ative drive ratios of the main and auxiliary rotors, above-mentioned the distributor element 52 of unit 1b will come into registration with a leading-out electrode 2 when the feeding-out electrode 55b of the rotor 6 comes into registration with the input terminal 4 of that unit, the distributor element 52 of unit 1c will come into registration with a leading-out electrode 2 when the feeding-out electrode 55c comes into registration with the input terminal of that unit, and the distributor element 52 of unit 1a will come into registration with the next succeeding leading-out electrode 2 when the feeding-out electrode 55d comes into registration with that unit. This process will repeat continuously as the shaft 19 is driven, and as a result current impulses will be fed by the main rotor to the auxiliary distributor units in succession and these impulses will in turn be distributed successively to the respective groups of leading-out electrodes 2 by the auxiliary rotors 3. The order of the firing or distributing positions in the distributor—that is the order of selection of the leading-out electrodes 2—will thus occur successively in the separate distributor units with successive electrodes in each distributor unit being selected at firing intervals of three. It will be seen that the eighteen leading-out electrodes of the distributor arrangement are each selected once by the rotor system as the main rotor 6 is driven through one and one-half revolutions and the auxiliary rotors 3 are each driven through one full revolution. With respect to a four-cycle engine, the main rotor is thus driven at three-fourths engine speed and the auxiliary rotors each at one-half engine speed.

It will be understood that current impulses supplied to the booster circuit will be distributed to the leading-out electrodes in the same manner as has been above described. However, to provide a suitable delay in the distribution of the booster current, the feeding-out electrodes 70 of the main rotor are set back from the respective preceding main electrodes 55 at a distance of one-third the interval between successive electrodes 55. As a result, the auxiliary distributor conductor elements 52 of each distributor unit will have moved past a leading-out electrode 2, by an amount of one-third the interval between adjacent electrodes, at the instant a booster feeding-out electrode 70 registers with the input terminal 4 of that unit. A relatively short gap between each distributor conductor element 52 and adjacent leading-out electrode 2, at the time the auxiliary distributor element is supplied with a booster current impulse, is however attained by making the auxiliary distributor elements relatively wide as is shown in Figure 2.

It will be seen that the embodiment above described constitutes an improved distributor arrangement wherein there is obtained a large spacing between successive distributing positions—a spacing from one distributor unit to the next. Furthermore, it will be seen that the successive firing or distributing positions selected within each distributor unit occur at a very much reduced rate—a rate proportional inversely to the number of distributor units provided, which in the present instance is at one-third the usual rate. The realization of these conditions results in the provision of a very large effective dielectric insulation between the successive distributing positions in the distributor; this large effective insulation enables the distributor to operate dependably and reliably under adverse conditions, such as at high altitudes where the di-

electric strength of the atmosphere is reduced, without encountering a bridging of successive distributing positions by the trailing arcs. Thus, the distributor arrangement is particularly well adapted for dependable and practical service in aircraft which employ large numbers of cylinders and which are to fly at high altitudes.

In Figures 6 and 7 there is illustrated a modified form of distributor as in accordance with my invention, the distributor being however shown in Figure 6 in connection with a magnet as is hereinafter explained. This modified distributor arrangement comprises a main distributor unit 75 and an auxiliary distributor unit 76. The auxiliary unit includes a plurality—there being two in the present instance—of separate distributors housed in one integral casing or shell 77. As is analogous to the embodiment above described, the main unit 75 is adapted to feed current to the separate distributors of the auxiliary unit in succession, and the separate auxiliary distributors are adapted to convey these impulses to the proper leading-out electrodes, all as is hereinafter described in detail.

The main distributor unit 75, which is herein illustrated as being of a commutator form but which may be of any other desired form, comprises a cylindrical rotor 78 of insulating material into which are molded two arcuate conductor segments 79 disposed along the periphery of the rotor. The conductor segments are each slightly greater than 90° in angular length and are symmetrically disposed about the axis of the rotor. Current is supplied to this unit by way of a conductor 80, and is fed out by the unit to two outgoing conductors 81 and 82. These conductors terminate in brushes—herein designated by the reference characters of the respective conductors with prime notation—which bear slidably against the periphery of the rotor. The brushes 81' and 82' are positioned at opposite sides of the brush 80' of the supply conductor, each at about 90° therefrom. It will be accordingly seen that the outgoing conductors 81 and 82 will become connected alternately by the conductor segments 79 to the supply conductor 80 at successive one-quarter revolutions of the rotor 78. In other words, the main distributing unit here shown is adapted to feed out current impulses to the outgoing conductors alternately and at the rate of four per revolution of the rotor 78; it will however be understood that the unit may be adapted to feed out any desired number of impulses per revolution, the number to be chosen depending upon the particular application to which the distributor arrangement is put as is hereinafter explained.

The auxiliary unit 76 has a housing shell 77 aforementioned which is circular and closed by a wall 77' at one end. This shell, which is molded in one integral piece as from any suitable insulating material, has embedded in the end wall 77' thereof two circularly arranged sets of leading-out electrodes 83 and 84. These sets of electrodes are disposed concentrically about the central axis of the shell. The electrodes of each set are spaced at equal angular intervals, the electrodes of one set being however offset from those of the other by one-half the angular interval between adjacent electrodes. At the open end of the shell 77 there is provided a distributor rotor 85 carried on a shaft 85' at the central axis of the shell. This rotor has two approximately radially opposite fingers of greater and lesser length which

terminate into inward extensions 86 and 87 at points in line with the sets of leading-out electrodes 83 and 84 respectively. Within these fingers there are embedded L-shaped conductor elements 88 and 89 respectively. These conductor elements project slightly beyond the tips of the fingers for registration with the respective sets of leading-out electrodes 83 and 84. The distributing conductor element 88 extends to the axis of the rotor 85 and there connects to a terminal 90 through a short post 91 riveted to the conductor element and journaled in a hollow inner end portion of the terminal. This terminal which is embedded in the end wall 77' of the housing shell, constitutes an input terminal for one of the distributors of the auxiliary unit and is connected to one of the two outgoing conductors leading from the main distributor unit 75, as to the conductor 81. The distributing conductor element 89 extends partially to the axis of the rotor and is riveted at its inner end to a conductor element 92. This conductor element carries a brush 93 at its other end which bears slidably against an annular ring 94 embedded in the end wall 77' of the distributor shell. This ring is connected to a terminal 95 which extends through the end wall 77'. This terminal constitutes an input terminal for the other of the distributors of the auxiliary unit 76 and is connected to the outgoing conductor 82.

To provide a large dielectric spacing between the elements of the separate distributors of the auxiliary unit 76, the housing shell 77 and rotor 85 are provided with interengaging parts of insulating material. These parts include a series of concentric flanges on the end wall 77' of the housing shell, which are a flange 96 between the sets of leading-out electrodes 83 and 84, a flange 97 between the inner set of leading-out electrodes 84 and the ring 94, and a pair of concentric flanges 98 and 99 between the ring 94 and the central input terminal 90. To the end above-mentioned, the rotor 85 has the inward extension 86 of the longer finger thereof interposed between the outer wall of the housing shell and the flange 96, and has the inward extension 87 of the shorter finger thereof interposed between the flanges 96 and 97. Also, the rotor 85 has a tubular extension 100 of insulating material embracing the conductor element 92 and interposed between the flanges 97 and 98, and has a central circular flange 101 which engages the annular recess provided between the flanges 98 and 99.

The fingers of the rotor 85 are oppositely directed as aforementioned, but are angularly spaced at less than 180° by an amount of one-half the angular interval between adjacent leading-out electrodes of each set. Thus, as the rotor 85 is turned the distributor conductor elements 88 and 89 will register alternately with successive ones of the respective sets of leading-out electrodes 83 and 84. In the present example, there are seven leading-out electrodes in each set to provide an ignition distributor for a fourteen-cylinder engine. Since the rotor 85 will register once with each of the leading-out electrodes of the auxiliary unit during each complete revolution thereof, and since the main distributor unit is capable of feeding out four current impulses per each revolution of its rotor 78, it follows that the rotor 78 is to be driven at three and one-half times the speed of the rotor 85. The drive shown in Figure 6, and hereinafter explained in detail, is adapted to drive these rotors at such relative speeds and, further, in such timed rela-

tionship that the supply conductor 80 is connected to the rotor distributor elements of the auxiliary distributors at the instants these elements register with successive ones of their respectively associated leading-out electrodes.

In driving the main and auxiliary distributors as above described, current impulses are fed alternately to the rotor distributing elements 88 and 89 and these elements convey the current impulses to successive ones of their respectively associated sets of leading-out electrodes. Since the succession of current impulses from the conductor 80 are distributed alternately by the main distributor unit 75 to the separate distributors 10 of the auxiliary unit, the frequency of the current impulses distributed by the auxiliary distributors is reduced to one-half from what it would be in a conventional distributor and, accordingly, for a given size of distributor, the effective dielectric spacing between successive leading-out electrodes is increased by substantially two times. Since the main distributor unit may be readily designed to avoid any appreciable bridging action and the auxiliary distributors 15 are effectively isolated from one another, it will be seen that a distributor arrangement constructed in accordance with the principles herein disclosed is particularly well suited to serve multi-cylindered engines for use in the rarified atmosphere where materially larger dielectric insulation 20 between successive distributing positions is required.

The distributor arrangement just described is particularly well adapted to, and is herein illustrated in Figure 6 in connection with, a magneto of the type disclosed in my application Serial No. 375,996, filed January 25, 1941, and entitled Magneto construction. In the magneto here referred to the flux controlling rotor is provided with a limited number of poles and the rotor is then driven above engine speed to provide the requisite number of ignition sparks per engine revolution. For instance, the magneto may have a four-pole permanent magnet rotor 102 carried on a shaft 102' and coaxing with field pieces, one of which is shown and referred to as 103, the field pieces being bridged by an ignition coil 104 having a high tension output terminal 105 connected to the supply conductor 80. For an engine of fourteen cylinders, as has been above referred to, the rotor 102 is driven to provide seven sparks per engine revolution or at one and three-quarters times engine speed. The rotor may be so driven from a drive shaft 106 rotated at seven-eighths engine speed, as through suitable gearing not herein shown, and coupled to the shaft 102' of the rotor through bevelled gearing 107 having a stepped-up transmission ratio of 2:1.

When the rotor 102 is provided with as many poles as the number of current impulses which the main distributor unit 75 is adapted to feed out per revolution of its rotor 78, these rotors are to be driven at the same speed and, accordingly, the distributor rotor 78 may be simply rigidly mounted on the magneto rotor shaft 102'. The rotor 85 of the auxiliary distributor unit, which is to rotate at two-sevenths the speed of the main distributor rotor 75 as aforementioned, may then be driven from the drive shaft 106 through gearing 108 having a stepped-down transmission ratio of 4:7.

It will be seen that the distributor arrangement of Figures 6 and 7 lends itself to being readily incorporated into the above-described magneto to provide a compact magneto and distributor ar-

angement capable of serving efficiently and dependably engines having large numbers of cylinders. For instance, the use of the main distributor unit 75 in conjunction with the auxiliary distributor unit 16 permits the latter to be made compactly and relatively small while yet providing a large dielectric spacing between successive firing or distributing positions within the auxiliary unit. Yet the main unit itself is of very small and simple construction and can be included in the magneto without any substantial addition in drive mechanism or in the size of the magneto.

In the foregoing detailed description certain preferred embodiments of my invention have been explained. It is however to be understood that no unnecessary limitation of my invention to the particular embodiments herein disclosed is intended as these embodiments are subject to many changes and modifications without departure from the scope of my invention, which I herein endeavor to express according to the following claims.

I claim:

1. In an ignition distributing system: the combination of a plurality of separate distributor units positioned at intervals about a predetermined axis and each having an input terminal and a distributor rotor; a main distributor rotor journalled at said axis to register with the input terminals of said units in recurring succession; and means to drive said main rotor and the separate rotors of said units in a predetermined timing relationship.

2. An ignition distributing system for carrying current impulses from a supply electrode to a series of leading-out electrodes in recurring succession, comprising a plurality of auxiliary distributor rotors for respective groups of said leading-out electrodes, the axes of said rotors being angularly spaced about a predetermined axis; a main distributor rotor journalled at said predetermined axis for feeding current impulses from said supply electrode to said auxiliary distributor rotors; and means to drive said rotors in predetermined timing relationship.

3. In an ignition distributing system including a drive shaft: the combination of a plurality of distributor units disposed at predetermined intervals about said shaft, each of said units including a series of leading-out electrodes and a distributing rotor for feeding current impulses to its said series of leading-out electrodes; a main rotor carried by said shaft for feeding current impulses to said auxiliary distributing rotors; and means to drive the rotors of said distributor units from said shaft.

4. In an ignition distributor including a housing having an opening for leading-out conductors: the combination of a main distributor rotor disposed centrally in said housing; a plurality of distributor units spaced about said main rotor and each having an input terminal positioned for

registration with said main rotor and a group of leading-out electrodes, each of said distributor units further having apertures for conductors to be connected to the respective leading-out electrodes, the apertures of each unit all terminating at one side of the unit; and means mounting said distributor units in said housing in positions wherein said apertures are directed towards the said opening of the housing.

5. A current distributing device comprising a housing provided with a central bearing; a plurality of separate distributor units mounted in said housing and spaced about said bearing as a center, said units each comprising a circular set of stationary electrodes and a rotor journalled at the center of said set, said rotor including a distributing electrode confronting the respective electrode set and an axially disposed terminal connected to said electrode; a main distributor rotor journalled in said bearing and adapted for feeding current impulses successively to the said terminals of said distributor units; and a drive for said main rotor and the rotors of said units adapted to drive the same in a fixed predetermined timing relationship.

6. A current distributing device comprising a housing provided with a central main bearing; a drive shaft journalled in said bearing; separate distributing units spaced at angular intervals about said bearing and respectively comprising circular stationary sets of leading-out electrodes and cooperating distributing rotors, said rotors being journalled to said housing and being provided with leading-in terminals; a main distributing rotor mounted on said shaft and adapted to register successively with the terminals of said units; and gearing in said housing drivingly coupling the rotors of said units to said shaft.

7. A current distributing device comprising a housing section provided with a central bearing; a series of separate distributor units disposed about said bearing and respectively having distributing rotors journalled to said housing, said rotors having leading-in conducting members mounted thereon; a drive shaft journalled in said bearing; a main rotor on said shaft adapted to register with said leading-in conducting members to feed current impulses to said separate distributor units; gearing drivingly connecting the rotors of said units to said shaft; and partitioning in said housing section forming a lubricating compartment for said gearing.

8. In an electrical distributor: the combination of a main distributor rotor; a plurality of auxiliary distributing means disposed at intervals about the axis of rotation of said main distributor rotor, each of said auxiliary distributing means including a distributor rotor, and said main rotor being adapted to register with the auxiliary rotors in recurring succession; and means to drive said main and auxiliary distributor rotors in predetermined timing relationship.
